UNITED STATES PATENT OFFICE.

WALTER H. BARBER, OF STONEHAM, AND RICHARD D. FAY, OF NAHANT, MASSACHUSETTS, ASSIGNORS TO SUBMARINE SIGNAL COMPANY, OF BOSTON, MASSACHUSETTS, A CORPORATION OF MAINE.

HYDROPHONE.

Application filed May 16, 1921. Serial No. 470,115.

To all whom it may concern:

Be it known that we, WALTER H. BARBER, of Stoneham, in the county of Middlesex and State of Massachusetts, and RICHARD D. FAY, of Nahant, in the county of Essex, in said State, both citizens of the United States, have invented a new and useful Improvement in Hydrophones, of which the following is a specification.

10 We have made a new and useful improvement in subaqueous sound receiving devices which are today known as "hydrophones". Our invention relates particularly to that class of hydrophone which is used primarily 15 to detect the sounds produced by a source having a definite pitch, such as a submarine bell, a struck rod or a submarine oscillator. While our invention is of value in the reproduction of sounds from any tuned source it 20 has unusual merit in the detection and reproduction of sounds from a source producing highly damped waves such as are created when a resonant body is struck under water.

25 When the resonant body such as a submarine bell is struck under water, the vibrations of the bell, which would continue for some time were the bell in an easily compressible medium such as air, are rapidly damped out so that probably only the first few vibrations 30 have sufficient energy to be audible at any considerable distance from the bell. Similarly the sound receiving surface or diaphragm of the hydrophone is very highly damped by the pressure upon it of the water 35 in which it is submerged, and as the diaphragm carries or is connected to the current-varying device, such damping tends to reduce the desired variations in the strength of the current.

40 Heretofore hydrophone diaphragms have been usually constructed of thin metal, probably with the expectation that such a diaphragm would respond most freely to the sound waves of small energy which reach 45 it. In such case, however, the diaphragm, because of its lack of body, is damped very materially by the water pressure so that it may be said only to be moved by each sound wave having sufficient energy to move it and to have but little, if any, free vibration of its own.

Attempts have been made to increase the amplitude of motion of the current-varying portions of microphones by mounting them

upon rods or tuning forks, but all such 55 methods require that the tuning member shall be mounted upon a diaphragm the surface of which is in contact with the water. If this diaphragm is thin, the weight of the tuning member and microphone button is 60 necessarily such that excessive damping occurs and the energy of succeeding sound waves is insufficient to build up the movements of the tuned member. If the diaphragm is large, such as the side of a ship, 65 the energy is insufficient to build up to any appreciable extent the movements of the tuned member with its associated microphone button. Up to the present time none 70 of these devices has been found practically useful.

The object of our invention is so to construct a hydrophone that its diaphragm will respond with the least possible resistance to the sound waves which first reach it, and, 75 because of its mass and resulting momentum, succeeding waves, even though of relatively small energy, will act to maintain it in motion notwithstanding the damping effect of the water with which it is in contact. The 80 other parts of our hydrophone are so designed, proportioned and arranged that the greatest possible amplitude of motion is imparted to the current-varying portions by 85 the sound waves which reach it.

We have overcome these defects in former devices of this character by making the diaphragm of the hydrophone of such proportions that it will vibrate freely with the microphone button attached to it; in other 90 words, the hydrophone as a whole is tuned so that it will vibrate with the same pitch or frequency under water as does the bell or other source of submarine sounds, but this tuning is dependent upon the diameter, material and 95 thickness of the diaphragm. We have therefore made the diaphragm of a suitable material and given it a thickness greater than has been usual in hydrophones hitherto made, so as to reduce the effect of damping 100 by water pressure which occurs when a thin diaphragm is used. We have found that for the usual submergence a diaphragm of phosphor bronze, about two tenths of an inch in thickness, will meet this requirement. 105 To obtain the necessary frequency of free vibration at the desired pitch of about 1215 per second we have used successfully a dia-

phragm about four inches in diameter. An instrument thus proportioned responds to the first wave from the source striking it and the succeeding waves tend to prolong 5 the vibrations of the diaphragm. The hydrophones which we have made using the above principles reproduce the clear ringing tone of the source and give a volume of reproduced tone far greater than has ever been obtained with the thin diaphragms hitherto employed.

A second feature of our hydrophone has added greatly to its efficiency when used on shipboard at sea where the hydrophone is 15 subjected to the noises produced by the ship's machinery and by the water which impinges upon the side of the ship near which the hydrophone is mounted. This second feature consists in the special form 20 which we have given to the current-varying means or microphone button which is mounted upon the diaphragm of the hydrophone. The microphone buttons, heretofore employed in hydrophones, utilize as the supports of the front electrodes highly elastic disks such as mica or spring metal. This arrangement results in giving to the button 25 a pitch of its own which is high, owing to the usual dimensions given to its several parts. Moreover, owing to the small inertia 30 of the moving parts of the button, the moving parts are easily set in motion and disturbing noises are produced frequently of sufficient intensity to overpower the note 35 from the source which it is desired to hear. This difficulty is particularly great when the pitch of the button approximates that of the source. As most microphone buttons 40 have been made to be mounted upon diaphragms, having small resonance when submerged, it has been usual to tune the buttons in order to increase their resonance to the sound waves from the source to the 45 pitch of the source. The result has been that when disturbing noises were great, it was frequently impossible to distinguish the notes of the source.

In our hydrophone we have tuned the 50 diaphragm and made it large and have used a button which is aperiodic or has a low natural pitch, a pitch far below that of the source. In fact, we have endeavored to make a button which has as little natural pitch 55 of its own (i. e. is as aperiodic) as possible. This we have accomplished by mounting the front electrode of the button upon a diaphragm of soft rubber and have subjected the rubber diaphragm to the least possible strain.

We have shown in the drawings the preferred form of device embodying our invention.

Figure 1 is a front elevation of our hydrophone; 60 Fig. 2 being a vertical section thereof.

Fig. 3 shows in section the separated elements of the microphone in assembled relation, and

Fig. 4 is a section of the assembled microphone.

1 is a heavy metal diaphragm made of elastic material which is tuned so as to have the greatest freedom of response, when submerged, for sound waves of the frequency of the source. This diaphragm is clamped 70 around its periphery to case 5 by clamping ring 2 which is secured to case 5 by a large number of screws, one of which is shown at 6. The casing 5 has an opening at the back through which the microphone may be inserted and which is closed by the screw plug 51. To prevent the ingress of water to the case at the diaphragm a ring of packing 4 is used and this packing ring is compressed 75 by pressure ring 3. A stud 8 of insulating material having therein a threaded socket is screwed into the centre of the inner face of diaphragm 1 and acts as the support of button 7. Button 7 has an insulating washer 15 in which are slots which form pockets 80 for the granular carbon 151 used as the current-varying medium. These slots must have their longer dimension horizontal when the button is in position and the hydrophone is supported from its stem or its cable 85 outside the case. To permit the greatest ease in mounting the button properly upon the diaphragm and to eliminate all lost motion between the button and the diaphragm, a locknut 9 is provided. In assembling the button in the hydrophone, the shank 90 of front electrode stud 19 (Fig. 3) is screwed as far as possible into the socket in stud 8 and still have the longer dimension of the granular carbon pockets horizontal. Locking nut 9, which had previously been screwed 95 upon electrode stud 19, is then turned up against stud 8 and thus firmly holds the button upon the centre of diaphragm 1. 10 and 11 are wires which connect the front 100 and back electrodes of the button with the wires leading through the watertight stem of case 5.

13 is the cup of the button which is made 105 of metal and has soldered to its bottom by solder 131 back electrode 14 of highly polished carbon or other conducting material, which does not readily oxidize. It has holes 132 to equalize the pressure within and without the microphone. A washer 15 of 110 felt or any other elastic non-conducting material is inserted in the cup and fills with the least possible compression the space between back electrode 14 and front electrode 18. Washer 15 is shown as having holes 115 which, when the washer is in place between 14 and 18, form two parallel cavities in which the granular carbon 151 is placed. When assembled in the button, the washer 15 is so 120 placed that the holes have their greatest 125 130

dimension horizontal. Front electrode 18 has a highly polished surface where it bears upon the granular carbon. Electrode 18 has been made of carbon in the buttons which we have manufactured but any conductor which can be highly polished and will not corrode may be used. Front electrode 18 is soldered to electrode stud 19 which has a threaded shank. The front electrode stud 19 is passed through a hole in the bottom of soft rubber cup 20. The bottom of rubber cup 20 thus forms a diaphragm for supporting the front electrode. Clamping washer 22 is next placed upon the shank of electrode stud 19 and locking nut 23 holds the clamping washer against the bottom of the rubber cup. When the button cup has received the felt washer and the holes in the felt washer have been filled with the required amount of granular carbon, the rubber cup with the front electrode is passed over the button cup and the sides of the button cup and the sides of the rubber cup are bound together by a whipping 21 of wire, thread or similar material. We have found that, if the pressure with which the front electrode stud is clamped upon the bottom of the rubber cup and the inside dimensions of the rubber cup and the outside dimensions of the button cup are correct, we can make a button which in itself has almost no natural frequency and that such frequency as inevitably must exist is far below that of the source of sound.

The use of the word aperiodic has been applied above to a microphone button having a low natural pitch, a pitch far below that of the source which is to be received. Broadly stated, however, the word aperiodic is not limited to a low natural pitch below that of the source to be received but is to be understood rather in the following broad interpretation. It is well known that most diaphragms or sound responsive devices respond more efficiently to sounds of certain pitches than of other pitches. The range of frequencies to which a receiving device such as a microphone may respond varies materially, depending upon the broadness of the tuning in the microphone or in the receiving device. If a microphone is highly resonant at the same frequency as the sound to be received the microphone is said to be highly tuned. By an aperiodic microphone we mean a microphone which is not particularly resonant; that is, has a broad resonance curve and in addition to this the resonant frequency lies far outside of the range in which it is desired to operate the microphone for sound reception. The resonant frequency of an aperiodic microphone or any sound responsive device may be far below the pitch of the source which it is desired to receive or may, on the other hand, be far above the pitch of such a source. If, over the range of reception in such cases, there is no resonance of the microphone, and the microphone responds as well to one frequency in the range of desired frequencies as to another, and no better, the microphone is said to be aperiodic. In the present case, while it is preferable in some instances to use a microphone which has a resonance below the frequency of the source which is to be received, nevertheless it is possible to use a microphone which has a resonance far beyond the resonance of the source to be received.

In the operation of the device described above an aperiodic microphone is combined with a highly resonant diaphragm. Not only is the mass of the microphone small as compared with that of the diaphragm but also the natural frequency of the microphone is far different from that of the diaphragm. Under such conditions the resonance curves of the two systems, in one case the diaphragm and in the other case the microphone, have their resonant frequencies widely separated. In coupling two such systems together the resonant frequencies remain practically unchanged and there results a high resonance point at the frequency of the diaphragm. In this case, therefore, it is possible to predict with great accuracy the frequency of the hydrophone, so that a hydrophone of a desired natural frequency may be easily obtained. In the case where the resonant frequencies of the individual systems lie somewhat close together the coupling of the two effects a shifting apart of the resonant frequencies, producing a resonance curve of the combined systems which may be fairly broad and not so sharply tuned to an individual frequency. There is, therefore, a distinct advantage in combining systems such as described above for not only is a highly tuned hydrophone obtainable in this way but also it is fairly simple to obtain the desired resonant frequency.

What we claim as our invention is:

1. A hydrophone comprising a tuned sound-receiving diaphragm of considerable thickness having a microphone button located thereon, said microphone being aperiodic.
2. A hydrophone comprising a thick highly tuned diaphragm and a microphone button mounted thereon and comprising a diaphragm of flexible material under substantially no tension and an electrode attached to said flexible diaphragm.
3. A hydrophone comprising a relatively thick highly tuned diaphragm and a microphone button comprising a metallic cup having an electrode mounted therein and a rubber cup having its sides enclosing entirely the sides of said metallic cup, a second electrode mounted within said rubber cup, said cups forming a chamber and resistance varying material within said chamber.
4. A hydrophone comprising a diaphragm

- and a microphone button mounted thereon, said diaphragm being relatively thick and tuned to respond most freely to sounds of a definite pitch and said button being adapted
5 to respond freely to sounds of a much lower pitch.
5. In a hydrophone, a tuned diaphragm and a microphone button attached thereto to vibrate therewith, said microphone but-
10 ton comprising a diaphragm of unstrained soft rubber and having one of its electrodes

attached thereto whereby the period of vi-
bration of said microphone will depend upon
the period of vibration of said tuned dia-
phragm.

15

6. A hydrophone comprising a highly reso-
nant diaphragm and an aperiodic micro-
phone button located thereon to be operated
thereby.
